UNITED STATES PATENT OFFICE.

JESSE B. HAWLEY, OF WILMETTE, ILLINOIS, ASSIGNOR, BY MESNE ASSIGNMENTS, TO ARVEY MANUFACTURING CO., A CORPORATION OF DELAWARE.

METHOD OF AND APPARATUS FOR FORMING FIBROUS-PULP RECEPTACLES.

Continuation of application Serial No. 461,131, filed April 13, 1921. This application filed April 1, 1925.
Serial No. 19,894.

This invention relates to the making of fibrous pulp containers, including the various steps of treating and handling the pulp during the formation of the container, apparatus for carrying the same into practice, and the article produced thereby.

This application is a continuation of an application filed by me, Serial No. 461,131, filed April 13th, 1921.

10 While I have illustrated and will describe my invention as applied in the production of a seamless fibrous pulp pail, I wish it to be understood that other forms of fibrous pulp containers, such as tubs, barrels, boxes and the like, may be made thereby, without departing from the spirit of my invention.

This invention contemplates the manufacture of a container, or the like, from such raw material as a cellulose fibrous material, 20 which is so handled in my improved process that the fibers are felted, which condition is intensified when pressure is exerted. The raw material thus treated to bring it into felted form possesses from two to three 25 times more strength than if the pulp were merely pressed, irrespective of any particular lay of the fibers. Also, by using this so-called felted process, a more compact wall is produced. Should it be desired to treat 30 containers made according to this process by subjecting them to a waterproofing or greaseproofing treatment, in the nature of a dip or an impregnator, a far better result is obtained, because there are fewer ends of the 35 fibers extending perpendicularly from the wall of the container to act as a wick. Also, by treating the pulp as contemplated in this invention, the pressing operation is greatly simplified.

40 Many important advantages are achieved by the present invention, among the more salient of which may be mentioned the following: A large percentage of the water is extracted from the pulp in the felting apparatus, thus leaving a smaller amount of water to be extracted in the pressing apparatus, which is the expensive part of the machine, both from the standpoint of initial cost and upkeep. The pulp in the felted 45 condition is much easier to handle in the press, due to the fact that there is not the tendency nor the opportunity for the fibers to get into the drainage system and into the dies. By having drainage on both the in-

side and the outside, that is, on the plunger 55 and on the inside or outside dies, the drainage surface is doubled, and the time of completing the pressing of the pail is very greatly reduced. This provision of inside and outside drainage in the pressing is very 60 important when using a felted blank. Another big advantage of using this felted process from a manufacturing standpoint is that after this felted blank is formed, even in its wet condition, it has sufficient strength 65 to be handled, without much danger of being broken, as distinguished from the old method, in which the receptacles being formed, even after pressing, are so flimsy 70 that unless care is used, they will be destroyed in handling. In addition to this greater strength which a felted pail or other receptacle has while still wet, the double drainage extracts the maximum amount of water, thereby simplifying the drying problem. Another advantage of importance under my improved process is that when the 75 pails or other receptacles are dried, and are ready to receive the hoops, handles, and the like, it is possible to cheapen the application 80 of sealing wires, handles, and the like, by the use of methods rendered possible because of the much greater strength and toughness of my improved felted containers, which would be impossible under the heretofore 85 known processes. The finished container is much stronger, comparative tests showing 90 it to be from three to four times stronger, tougher and in every way more durable and more satisfactory than containers made under the old processes of molding.

95 By the heretofore known processes of forming fibrous pulp containers, the pulp has been merely introduced in a mass into a press or form, without regard to the lay or arrangement of the fibers with relation to each other and presseed into shape. In the present invention, as pointed out above, I so treat and handle the pulp that the fibers 100 will fall in criss-cross relation, thus becoming felted, and adding very greatly to the strength of the pail or other container, before as well as after being pressed, calen- derized, or otherwise treated in finishing.

105 Among the objects of my invention, therefore, are to provide an improved method of manufacturing fibrous pulp containers, or the like; further to provide improved apparatus

for reducing this method to practice; further to produce an improved fibrous pulp container or the like; further to felt or lay the fibers across each other so that they will be substantially woven together in interlocking relation; further to so form and treat the fibrous pulp pail or other container that it may be more readily and safely handled, while still green and before pressing; further to produce a pail or other container which when completed will more readily and effectively take and hold the sealing wires, hoops, handles and the like, without danger of the same being pulled out; further to improve the pressing operation by providing drainage through the pressing members on both the inside and outside of the receptacle being formed; further to provide a tougher, stronger and more durable fibrous pulp container than heretofore known; and such further objects, advantages and capabilities as will later more fully appear.

My invention further resides in the combination, construction and arrangement of parts illustrated in the accompanying drawings, and while I have shown therein preferred embodiments of apparatus for carrying my improved process into effect, I desire it to be understood that the same are susceptible of modification and change without departing from the spirit of my invention.

In the drawings:

Fig. 1 is a vertical sectional side elevational view through one form of my improved apparatus for forming the pail blanks.

Fig. 2 is an enlarged fragmentary vertical section through the lower portion of the apparatus of Fig. 1, also showing the form in cross section.

Fig. 3 is a section on line 3—3 of Fig. 1.

Fig. 4 is a sectional view of the apparatus of Fig. 1, showing the felted blank as it appears prior to the pressing operation.

Fig. 5 shows the felted blank removed from the form.

Fig. 6 is a vertical sectional view of a press in which the pail blanks are pressed into final form, and showing the blank after being placed on the plunger prior to elevating the same to the dies.

Fig. 7 is an enlarged sectional view, showing the plunger with the pail blank between the dies.

Fig. 8 is a vertical sectional view of a finished pail made by the process of the present invention.

In the form of apparatus illustrated in Fig. 1, the pulp 1 in a thin condition is poured into tank 2, through the inlet pipe F, in which is mounted any suitable form of valve 4, and which tank 2 is mounted upon a suitable bottom member 5 in substantially air-tight relation. Slidably mounted in tank 2 is the pressure head 3, which will be here-

inafter more fully explained. In the bottom of tank 2, and upon the floor portion 5, is positioned the form 6, of a shape corresponding to that desired in the container being manufactured. This form may be of any suitable material, such as metal, cloth, wood, or the like, and has its side and bottom portions perforated as shown at 7. Closely surrounding the sides and bottom of the form is a fine mesh screen 8, which may be of any suitable material, such as metal, cloth, or the like. This screen overlies the apertures 7 in the form, and being of fine mesh prevents the entry of the pulp fibers into the apertures.

Extending through bottom portion 5 to the space within form 6 is pipe 9, which will have connection with any suitable suction producing means to maintain a partial vacuum within form 6. To facilitate the feltting of the pulp fibers on the form, I have provided vibrating means for vibrating both the tank and the form, and which comprises eccentrics 10 and 11, driven by any suitable motor 12, and operating in eccentric straps slidably positioned at the inner ends of levers 12' and 13, pivoted at 14 and 15, respectively, and having pivotally connected at their outer ends links 16 and 17, the former of which is connected at 18 to the side of the tank wall to vibrate the same. Vibration of form 6 is affected through link 17 by connecting the same to a suitable ring, or the like, 19, extending upwardly from which are spaced arms 20, carrying at their upper ends spider 21 which, as shown in Fig. 3, comprises a plurality of pointed arms 22, touching the inner surface of the form, so that vibration of ring 19 will in turn vibrate the form. The amount of vibration to which these parts are subjected is preferably small, and is employed to facilitate the more ready felting of the fibers upon the form.

Assuming tank 2 to be filled with thin pulp, as shown in Fig. 1, a suction will then be created within form 6, through pipe 9, the action of which will be to draw the thin pulp to the sides and bottom of the form, the water passing through the apertures 7, and the fibers being arrested by screen 8. This action will cause the fibers to arrange themselves substantially in criss-cross or felted relation, which felting action, as stated above, may, if desired, be accelerated and assisted by vibration of either or both of the tank and the form.

Also, if desired, pressure may be applied during this operation by forcing head 3 downwardly against the pulp. These operations I may vary, if desired, for example, I may either apply a partial vacuum within the form prior to the application of the pressure on the pulp, I may apply these simultaneously, or I may reverse these operations.

and apply the pressure first. Also, I may at times desire to omit pressure from head 3, and permit the thin pulp to settle by gravity, assisted if desired by suction through apertures 7 of the form. Thus by varying the sequence of these steps, I am enabled to vary the condition of the finished form of the pulp, as desired.

Fig. 4 shows the plunger 3 in its lowered position, and the fibers of the pulp collected against the sides and bottom of the form, it being understood that the water in the thin pulp originally placed in the tank has been withdrawn through apertures 7, and suction pipe 9. It will thus be obvious that I am enabled to withdraw a very considerable amount of the water in the pulp from the blank thus formed, which greatly facilitates and shortens the pressing and finishing operations. The pail blank of Fig. 4, after removal from form 6, is shown in cross-section in Fig. 5.

After the blank has been formed in the apparatus heretofore described, to bring the pulp into felted condition with its fibers lying in criss-cross relation, the blank is then ready to be transferred to the press, which may be done by leaving the blank and form together and applying the form over the plunger head or, when desired, by removing the blank from the form and applying the blank alone to the plunger head. Due to the fibers of the blank being felted, the blank will possess sufficient strength to be handled without the form, before pressing, if desired. One form of press is shown in Figs. 6 and 7, the former of which views shows the plunger head 40 in lowered position with the blank applied thereto. Fig. 7 is an enlarged cross section, showing the plunger head as being elevated to bring the blank between the die members 41. These dies are moved inwardly through action of the toggle joint members 43, through suitable coating parts to compress the fibers of the blank against the plunger head 40. Simultaneously with the compression movement of dies 41, the die 42 for forming the pail bottom, is lowered, and functions to press said bottom to final form. It is of importance to note that the plunger head 40 is provided with a plurality of perforations 44 throughout its sides, and is grooved throughout its upper surface, as shown at 45. There are also formed in the sides of the plunger head a series of channels or grooves 46 having connection with said apertures 44. The function of these grooves and apertures is to provide ready drainage for the moisture in

the blank being pressed, and in order to prevent entry of any of the fibers into these grooves and apertures, the plunger is provided with a fine mesh covering indicated generally at 47. To provide ample and free drainage for the exterior of the blank, grooves 48 are formed in the inner faces of dies 41, and openings 49 and grooves are formed in die 42. To prevent entry of fibers thereinto, grooves 48 and 50, and apertures 49 are covered with fine mesh screens 51 and 52, respectively, as seen in Fig. 6. This arrangement gives ample and complete drainage from both sides of the blank being pressed, and is of vital importance in pressing felted blanks. A finished felted pressed pail is shown in Fig. 8.

In place of the steel dies, I may also use a rubber bag, which will greatly simplify matters and permit the making of various sizes of pails with slight changes in the press. Since the size of tank 2 may be varied, as desired, it will be seen that in the above invention, I am able to prepare and lay the fibers in criss-cross relation and measure the amount of pulp necessary for the blank being formed.

I claim as my invention:

1. A method of forming fibrous pulp containers, comprising applying thin pulp to the exterior of a perforated form of the desired shape positioned to have fine pulp applied thereto from a pulp containing vessel, and vibrating the vessel to assist the pulp fibers to felt, and applying pressure to the pulp contained in said vessel.

2. A method of forming fibrous pulp containers, comprising applying thin pulp to the exterior of a perforated form of the desired shape positioned to have fine pulp applied thereto from a pulp containing vessel, and vibrating the vessel to assist the pulp fibers to felt on the form, applying pressure to the pulp contained in said vessel, and creating a suction through said perforations.

3. In apparatus of the class described, a chamber for receiving and holding thin pulp, a form associated with said chamber and adapted to have pulp applied thereto from said chamber, and means to vibrate the chamber walls.

4. In apparatus of the class described, a chamber for receiving and holding thin pulp, a perforated form associated with said chamber and adapted to have pulp applied thereto from said chamber, and means to vibrate the chamber walls, and means to create a suction through said perforations.

JESSE B. HAWLEY.
